(57) **CLAIM**

The ornamental design for a square step light, as shown and described.

DESCRIPTION

FIG. 1 is a perspective view of a square step light according to our new design;

FIG. 2 is a top view thereof;

FIG. 3 is a front view thereof;

FIG. 4 is a first side view thereof;

FIG. 5 is a second side view thereof;

FIG. 6 is a bottom view thereof; and,

FIG. 7 is a back view thereof.

The broken lines shown in the drawings are for the purpose of illustrating portions of the light and form no part of the claimed design.
